US00D537253S

(12) **United States Design Patent** (10) **Patent No.:** **US D537,253 S**
Chen (45) **Date of Patent:** **** Feb. 27, 2007**

(54) **TOOLBOX**

(76) Inventor: **Tsai-Ching Chen**, No. 202, Lane 330,
Sec. 7, Chang Lu Road, Fu Hsing
Hsiang, Chang Hua Hsien (TW)

(**) Term: **14 Years**

(21) Appl. No.: **29/226,318**

(22) Filed: **Mar. 28, 2005**

(30) **Foreign Application Priority Data**

Oct. 14, 2004 (EM) 000239363

(51) LOC (8) Cl. **03-01**

(52) U.S. Cl. **D3/905**; D3/315

(58) **Field of Classification Search** D8/71,
D8/85; D3/319, 315, 201, 284, 295; 81/490,
81/117.4; 206/377, 349, 373, 375, 378

See application file for complete search history.
